UNITED STATES PATENT OFFICE

95,301

DESIGN FOR AN ELECTRIC HEATER

Frederick B. Adam, Huntleigh Village, Mo., assignor to Frank Adam Electric Company, St. Louis, Mo., a corporation of Missouri

Application February 18, 1935, Serial No. 55,480

Term of patent 7 years

To all whom it may concern:

Be it known that I, Frederick B. Adam, a citizen of the United States, residing in Huntleigh Village, county of St. Louis, and State of Missouri, have invented a new, original, and ornamental Design for an Electric Heater, of which the following is a specification, reference being had to the accompanying drawing, forming part thereof.

In the drawing, Fig. 1 is a front elevation of an electric heater showing my new design; Fig. 2 is a side elevation; and Fig. 3 is a top plan view of the same.

I claim:

The ornamental design for an electric heater, substantially as shown.

FREDERICK B. ADAM.
